UNITED STATES PATENT OFFICE

2,624,011

SELF-DEVELOPING POCKET RADIATION DOSIMETER

Kurt G. Stern, New York, N. Y.

Application March 27, 1951, Serial No. 217,710

16 Claims. (Cl. 250—65)

1

This invention relates to radiation detecting devices, and more particularly to a radiation detector of the photographic type.

A main object of the invention is to provide a novel and improved radiation detector of the photographic type having self-contained means for developing the photographic element thereof.

A further object of the invention is to provide an improved radiation detector of the photographic type having self-contained means for developing the radiation-sensitive element thereof, said detector being simple in construction, compact in size, and easy to manipulate.

A still further object of the invention is to provide an improved radiation detecting unit of the self-developing type, wherein no darkroom facilities are required to develop the radiation-sensitive element thereof and wherein said element is effectively shielded from visible radiation at all times prior to development thereof, whereby false and misleading indications are avoided.

A still further object of the invention is to provide an improved radiation detector of the photographic type which may be conveniently worn or carried by an individual in order to detect or gauge exposure of the individual to ionizing radiation, such as gamma radiation, said detector having self-contained means for developing the radiation-sensitive element thereof, and having means for shielding said element against light during the process of development thereof as well as during the period of normal wearing thereof by the individual, whereby no darkroom facilities are required for developing the element to determine the degree of exposure thereof to ionizing radiation, the device incorporating its own developing chemicals and being arranged so that said chemicals may be readily and conveniently utilized in the unit when it is desired to develop said radiation-sensitive element.

A still further object of the invention is to provide an improved radiation detector of the photographic type having self-contained means for developing the radiation-sensitive element thereof, said detector comprising inexpensive parts, being reliable in operation, and being usable over and over again by the renewal of the disposable elements thereof.

Further objects and advantages of the invention will become apparent from the following description and claims, and from the accompanying drawings, wherein:

Figure 1 is a front elevational view of an improved self-developing pocket radiation dosimeter constructed in accordance with the present invention.

2

Figure 2 is a cross-sectional view taken on line 2—2 of Figure 1.

Figure 3 is a perspective view, partly broken away, of one form of cartridge for developing materials which may be employed in the dosimeter of Figures 1 and 2.

Figure 4 is a perspective view of the dosimeter of Figures 1 and 2 with the developer end cap and developer cartridge removed.

10 Figure 5 is an enlarged cross-sectional view taken on line 5—5 of Figure 2.

Figure 6 is a perspective view of the dosimeter of Figures 1 and 2, partly broken away, and showing the indicator end plug and the photographic element partly withdrawn from the casing of the dosimeter subsequent to development of the photographic element.

Figure 7 is a front elevational view of a photographic element employed in the dosimeter, said element being shown in its unrolled position.

Figure 8 is a longitudinal cross-sectional view taken through an alternative form of developer cartridge which may be employed in the pocket dosimeter of the present invention.

25 Figure 9 is an enlarged longitudinal cross-sectional view taken through the lower portion of a modified form of radiation dosimeter unit constructed in accordance with the present invention.

Reference is made to applicant's copending applications, Serial No. 182,830, filed September 1, 1950, for "Radiation Detector," and Serial No. 215,053, filed March 12, 1951, for "Film Badge Radiation Detector," containing related subject matter, and containing descriptions of associated types of radiation detectors employed for purposes similar to that for which the radiation dosimeter of the present invention is employed.

Referring to the drawings, the improved radiation detecting unit is designated generally at 11. The unit 11 comprises a cylindrical housing 12, in one end of which is removably secured the plug member 13. Said plug member has a reduced inner portion 14 and is secured in the end of housing 12 in any suitable manner, as for example, by a tight friction fit. Secured to the reduced inner portion of plug member 13, as by a plurality of strips of adhesive tape 15 is the cylindrically-rolled radiation indicator tab 16. Tab 16 comprises a rectangular flexible card-board body 17 on which is longitudinally and centrally secured a strip 18 of photographic paper, such as Kodabromide No. 4 paper, as manufactured by the Eastman Kodak Company, Rochester, New York. As shown in Figure 7, 30 the test strip 18 is flanked on both sides by a

comparison scale which is subdivided into six steps in the form of respective bands extending transversely to strip 18 and printed in different shades of gray, corresponding to an overall exposure range from zero to 600 roentgens. The gamma exposure ranges indicated on the individual steps of the comparison scale are shown in the following table:

Scale Step Designation	Exposure Range in Roentgens
A	0-50
B	50-100
C	100-200
D	200-300
E	300-400
F	400-600

The gamma exposure ranges marked on the comparison scale shown in the above table may obviously be modified to fulfill specific requirements of the medical authorities, or to correspond more closely to the radiation response characteristics of the photographic material employed.

For further details concerning the construction and use of the radiation detector tab 16, reference is made to applicant's copending application, Serial No. 215,053, filed March 12, 1951, as mentioned above.

As shown in Figures 5 and 6, the indicator tab 16 may be curled into a generally cylindrical shape with the radiation sensitive element 18 facing inwardly.

Designated at 20 is an axially extending sleeve member which is rigidly carried by a bushing 21 threadedly secured in the end of housing 12 at the end thereof opposite plug member 13. An annular sealing gasket 22 may be employed between the head of bushing 21 and the rim of housing 12, as shown in Figure 2. The sleeve member 20 extends substantially the entire internal length of housing 12 between plug member 13 and bushing 21, and is formed with a longitudinal slot 23 located adjacent to and substantially midway between the side edges 19, 19 of the indicator tab 16 when the parts are assembled in the manner shown in Figure 5. The plug member 13 and housing 12 may be provided with registrable index marks 24 and 25 to insure the proper registration of the slot 23 with the space between the tab edges 19, 19 when the unit is thus assembled. With the slot 23 in this position, the cylinder 20 acts as a light trap, making it possible to open the dosimeter in bright daylight or artificial light without exposing the photographic strip 18 to actinic light.

Designated at 26 in an inner hollow cylinder or cartridge, containing developing materials, which is contained in the sleeve 20. A closure plug 27 is axially threaded into the bushing 21. The bushing 21 is formed with a conical, funnel-like surface 28 and the plug 27 is provided with a mating conical surface 29 which is sealingly engageable with funnel surface 28.

The cartridge 26 may comprise a deformable plastic shell having frangible ends, said shell containing fixing solution and an inner capsule 30 of frangible, deformable plastic material containing developing powder. The housing 12 and the inner cylinder 20 may be of any suitable light-opaque, rigid material, such as thin metal or plastic. The housing 12 is of a material which is opaque to visible light but penetrable to gamma radiation, such as thin aluminum or plastic tubing. The housing 12 may be provided with a con-

ventional pocket clip 31, whereby the unit may be carried in the user's pocket in the manner of a fountain pen.

Where it is desired to process the radiation-indicator tab 16, the closure plug 27 is unscrewed and the cartridge 26 is removed. Said cartridge is squeezed or otherwise manipulated to break the inner capsule 30, and one end of the cartridge is broken. The contents of the cartridge are emptied into the housing 12 through the funnel like opening of bushing 21. The closure cap 27 is then screwed into the bushing 21 into sealing position thereon and the unit is thoroughly shaken to bring the developing materials into contact with the photographic strip 18 for a sufficient length of time to completely develop strip 18. The plug member 13 is then withdrawn from the end of housing 12, whereby the indicator tab 16 is removed from said housing, as shown in Figure 6. The tab 16 is then detached from the plug 16 and may be then examined to determine the degree of exposure of the unit to ionizing radiation.

As an alternative, the inner cartridge may comprise a deformable, frangible plastic shell 26' provided with a transverse inner partition wall 27', as shown in Figure 8, dividing the cartridge into two compartments. One compartment may contain developing solution 28' and the other compartment may contain fixing solution 29'. In processing the indicator strip, the cartridge is removed and the left end of the cartridge is first broken. The developer solution is poured into the housing through bushing 21 and plug 27 is secured thereon. The unit is shaken thoroughly for a sufficient period to develop the photographic strip 18. The plug 27 is then removed, the other end of cartridge shell 26' is broken, and the fixing solution 29' is introduced into the housing 12 through bushing 21. The plug 27 is replaced and the unit is shaken thoroughly to fix the developed strip 18. Plug 13 may then be removed to withdraw the indicator tab 16 for examination, as above described.

As a further alternative, the partition wall 27' may be relatively thin and frangible. When the developing materials are to be introduced into the housing, the cartridge 26' may be squeezed so as to break said partition wall, and the contents of the cartridge may then be squeezed out of one end thereof into the housing through bushing 21.

After use of the unit, the internal parts thereof may be cleaned and the unit may be refitted in a suitable darkroom with a new indicator tab 16. A new cartridge of developing and fixing materials is then provided in the sleeve 20, whereby the unit is ready for further use.

In the modified form of the pocket dosimeter illustrated in Figure 9, an equalizing filter 32, made of suitable metal, such as sheet cadmium, lead or silver, in the form of a band, may be provided between the outer housing shell, shown at 12', and the strip of photographic material 18. Where cadmium is employed, the preferred thickness of the band 32 is 1 mm. The filter 32 protects the photographic emulsion of strip 18 against hard beta and soft gamma rays and also acts to insure that the photographic emulsion will register equal amounts of gamma radiation with the same density independently of the wave length over a wide range of the gamma energy spectrum (from approximately 0.1 to 10 m. e. v.).

As shown in Figure 9, the bottom of the housing of the unit may comprise a disc 33, secured to

the housing body by a layer 34 of suitable sealing composition, such as is conveniently employed in sealing corks on bottles. This composition may be applied in a liquid state by dipping the shell, with the disc 33 in place thereon, into the molten sealing mixture. Shellac, sealing wax, and cellulose plastics are suitable materials for seals of this type. The finished seal may be marked by impressing a date or other information onto its periphery. When the dosimeter is opened to remove the indicator tab for examination after processing, the seal would be fractured, thus indicating that the device had been opened.

The inner chemical cartridge may take many different forms, depending on the contents and the processing technique employed. The cartridge or vial may be made of pliable plastic, such as Teflon, Polythene, or the like. It may be filled with a single developer-fixer (or stabilizer) composition, employing a single compartment in the cartridge, or the components may be separated by employing an inner capsule or a partition wall such as 27' in Figure 8.

As above explained, the slotted inner cylinder 20 functions as a light trap, making it possible to open the dosimeter at the top (by removing plug 27) in bright daylight or artificial light for the purpose of removing the cartridge of developing materials and emptying its contents into the inner cylinder 28 without exposing the photographic strip 18 to actinic light.

It will be further noted that the photographic strip 18 is preferably arranged parallel to the axis of the dosimeter shell and is located opposite the slot 23 of the inner cylinder 28. In this manner, any actinic radiation which may enter the dosimeter upon removal of plug 27 is prevented from reaching the strip 18 through the slot 23. The primary function of said slot is to admit the processing chemicals from the cartridge 26 or 26' into the annular space between the inner and outer cylinders, and at the same time to allow air to escape from the annular space into the upper portion of inner cylinder 28. The above arrangement prevents air from being trapped in the annular space and interfering with the developing process.

In the arrangement of Figures 2 and 6, the indicator tab 16 is shown attached to the reduced portion 14 of plug 13 with the photographic strip 18 facing inward. Alternatively, the tab 16 may be secured to the inner wall surface of outer cylinder 12 with strip 18 facing inwardly or to the outer surface of inner cylinder 28 with strip 18 facing outwardly, whereby sufficient clearance will be provided adjacent the surface of strip 18 to allow proper access of the developing chemicals to the photographic strip during the processing of the indicator tab. Experiments have indicated that at least two millimetres clearance is required in order to insure free access of the chemical solutions to the photographic strip and to avoid the trapping of air bubbles on the surface thereof.

While certain specific embodiments of an improved pocket radiation dosimeter have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In a radiation detector, an elongated housing of material opaque to light and penetrable to ionizing radiation, an elongated light-opaque sleeve secured longitudinally in said housing and

defining a space between the sleeve and the internal surface of the housing, said sleeve opening at one end of the housing, a radiation-sensitive tab element in said space arranged around said sleeve, and means covering the other end of the housing.

2. In a radiation detector, an elongated housing of material opaque to visible light and penetrable to ionizing radiation, an elongated core member secured longitudinally in said housing and defining a space between the core member and the internal surface of the housing, and a radiation-sensitive tab element in said space arranged around said core member.

3. In a radiation detector, an elongated housing of material opaque to visible light and penetrable to ionizing radiation, an elongated sleeve member secured longitudinally in said housing and defining a space between the sleeve member and the internal surface of the housing, and a radiation-sensitive tab element in said space arranged around said sleeve member.

4. In a radiation detector, an elongated housing of material opaque to visible light and penetrable to ionizing radiation, an elongated sleeve member secured longitudinally in said housing and defining a space between the sleeve member and the internal surface of the housing, and a radiation-sensitive tab element in said space arranged around said sleeve member, said sleeve member opening at one end of said housing.

5. In a radiation detector, an elongated housing of material opaque to visible light and penetrable to ionizing radiation, an elongated sleeve member secured longitudinally in said housing and defining a space between the sleeve member and the internal surface of the housing, and a radiation-sensitive tab element in said space arranged around said sleeve member, said sleeve member opening at one end of the housing and being formed in its wall with an aperture located opposite said tab element.

6. In a radiation detector, an elongated housing of material opaque to visible light and penetrable to ionizing radiation, an elongated sleeve member secured longitudinally in said housing and defining a space between the sleeve member and the internal surface of the housing, a radiation-sensitive tab element in said space arranged around the sleeve member, said sleeve member opening at one end of the housing and being formed in its wall with an aperture located opposite said tab element, and an elongated, frangible container disposed inside said sleeve member, said container being adapted to carry developing materials.

7. In a radiation detector, a tubular housing of material opaque to light and penetrable to ionizing radiation, an annular bushing secured to one end of said housing, a sleeve member secured to said bushing and extending longitudinally in said housing, said sleeve member defining an annular space between the sleeve member and the internal surface of the housing, a photographic tab element in said space arranged around said sleeve member, and means covering the other end of said housing, said sleeve member being formed with a longitudinal slot located opposite said tab element.

8. In a radiation detector, a tubular housing of material opaque to light and penetrable to ionizing radiation, an annular bushing secured to one end of said housing, a sleeve member secured to said bushing and extending longitudinally in said housing, said sleeve member defining an annular space between the sleeve member and

the internal surface of the housing, a photographic tab element in said space arranged around said sleeve member, means covering the other end of said housing, said sleeve member being formed with a longitudinal slot located opposite said tab element, whereby the sleeve member defines a light trap, an elongated, frangible container disposed in said sleeve member, said container being adapted to carry developing materials, and a plug member detachably secured in said bushing.

9. In a radiation detector, a tubular housing of material opaque to light and penetrable to ionizing radiation, an annular bushing secured to one end of said housing, a sleeve member secured to said bushing and extending longitudinally in said housing, said sleeve member defining an annular space between the sleeve member and the internal surface of the housing, a closure plug removably secured in the other end of said housing, and a photographic tab element secured to said plug and arranged around said sleeve member in said space.

10. In a radiation detector, a tubular housing of material opaque to light and penetrable to ionizing radiation, an annular bushing secured to one end of said housing, a sleeve member secured to said bushing and extending longitudinally in said housing, said sleeve member defining an annular space between the sleeve member and the internal surface of the housing, a closure plug removably secured in the other end of said housing, and a photographic tab element secured to said plug and arranged around said sleeve member in said space, said sleeve member being formed with a longitudinal slot located opposite said tab element, providing a passage for the flow of developing liquid into said annular space while preventing light from reaching the tab element.

11. In a radiation detector, a tubular housing of material opaque to light and penetrable to ionizing radiation, an annular bushing secured to one end of said housing, a sleeve member secured to said bushing and extending longitudinally in said housing, said sleeve member defining an annular space between the sleeve member and the internal surface of the housing, a closure plug removably secured in the other end of said housing, a photographic tab element secured to said plug and arranged around said sleeve member in said space, said sleeve member being formed with a longitudinal slot located opposite said tab element, providing a passage for the flow of developing liquid into said annular space while preventing light from reaching the tab element, an elongated, frangible container disposed in said sleeve member, said container being adapted to carry developing materials, and a plug member detachably secured in said bushing.

12. In a radiation detector, a tubular housing of material opaque to light but substantially transparent to ionizing radiation, a core member longitudinally secured in said housing and defining a space between the core member and the internal surface of the housing, a photographic tab element in said space arranged around said core member, an equalizing filter of

sheet material partially opaque to ionizing radiation arranged between said tab element and the internal surface of said tubular housing.

13. In a radiation detector, a tubular housing of material opaque to light but substantially transparent to ionizing radiation, a tubular core member longitudinally secured in said housing, and defining a space between the core member and the internal surface of the housing, a photographic tab element in said space arranged around said core member, an equalizing filter of sheet material partially opaque to ionizing radiation arranged between said tab element and the internal surface of said tubular housing, said core member being formed with an aperture located opposite the tab element, providing a passage for the flow of developing liquid into said space while preventing light from reaching the tab element, and a removable plug element secured in one end of said core member.

14. In a radiation detector, a tubular housing of material opaque to light but substantially transparent to ionizing radiation, and a hollow core member longitudinally secured in said housing and defining a space between the core member and the internal surface of the housing, said core member being formed with a longitudinal slot, said core member being adapted to receive developing liquid and said slot defining a passage for the flow of developing liquid from said core member into said space.

15. In a radiation detector, a tubular housing of material opaque to actinic light but substantially transparent to ionizing radiation, and a hollow sleeve member longitudinally secured in said housing and defining a space between the sleeve member and the internal surface of the housing, said sleeve member extending for the major portion of the internal length of said housing and being formed with a longitudinal slot, said sleeve member being adapted to receive developing liquid and said slot defining a passage for the flow of developing liquid from the sleeve member into said space.

16. In a radiation detector, a tubular housing of material opaque to actinic light but substantially transparent to ionizing radiation, a hollow core member longitudinally secured in said housing and defining a space between the core member and the internal surface of the housing, said core member being formed with a longitudinal slot, said core member being adapted to receive developing liquid and said slot defining a passage for the flow of developing liquid from said core member into said space, and a removable plug element secured in the end of said core member.
